UNITED STATES PATENT OFFICE.

THOMAS M. FARNILOE, OF WEST SMITHFIELD, LONDON, ENGLAND.

DESIGN FOR ROLLED GLASS.

46,896.

Specification for Design.

Patented Feb. 2, 1915.

Application filed October 10, 1914. Serial No. 866,139. Term of patent 14 years.

To all whom it may concern:

Be it known that I, THOMAS MEAKIN FARNILOE, a subject of the King of England, residing at 34 St. John street, West Smithfield, London, England, have invented a new, original, and ornamental Design for Rolled Glass, of which the following is a specification, reference being had to the accompanying drawing, forming part thereof.

The figure is a plan view of a portion of

a sheet of rolled glass illustrating my new design.

I claim:

The ornamental design for rolled glass, as shown.

THOS. M. FARNILOE.

Witnesses:

J. B. SCOTT,
GEO. F. FARNILOE.
